UNITED STATES PATENT OFFICE.

WILLIAM KENNER, OF SEATTLE, WASHINGTON.

DESIGN FOR AN AUTOMOBILE VASE-HOLDER.

56,006.

Specification for Design.

Patented Aug. 10, 1920.

Application filed October 27, 1919. Serial No. 333,853. Term of patent 3½ years.

To all whom it may concern:

Be it known that I, WILLIAM KENNER, a citizen of the United States, residing at Seattle, in the county of King and State of Washington, have invented a new, original, and ornamental Design for an Automobile Vase-Holder, of which the following is a specification, reference being had to the accompanying drawings, forming part thereof.

In said drawings, Figure 1 is a perspective view of a vase holder showing my new design, a vase being indicated therein by dotted lines.

Fig. 2 is a side elevational view of the vase holder. Fig. 3 is a plan view, shown partly in horizontal section. Fig. 4 is a front elevational view.

I claim:

The ornamental design for an automobile vase-holder, as shown.

WILLIAM KENNER.
